UNITED STATES PATENT OFFICE.

WARREN W. CARPENTER, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 11, 1919. Serial No. 310,068.

To all whom it may concern:

Be it known that I, WARREN W. CARPENTER, a citizen of the United States, residing at Brooklyn, in the county of Kings, State 5 of New York, have invented certain new and useful Improvements in Telephone-Exchange Systems, of which the following is a full, clear, concise, and exact description.

This invention relates to improvements in 10 telephone exchange systems and has particular reference to switching means therefor.

Broadly, the system of the present invention includes a plurality of subscribers' lines served by a lesser number of link circuits, 15 any one of which may be seized upon the initiation of a call to interconnect a calling with a called subscriber.

An object of the invention is to provide 20 novel means whereby the calling and called lines are simultaneously connected to the seized link circuit upon the selection thereof.

Another object is the provision of an impulse controlling mechanism common to a 25 plurality of subscribers' lines and operable in response to the transmission of a set of impulses from the calling subscriber's substation to initially actuate a set of counting relays included therein and then effect the 30 selection of an idle link circuit.

The inventive idea involved is capable of 35 receiving a variety of expressions one of which, for the purpose of illustrating the invention, is shown in the accompanying drawings; but it is to be expressly understood that said drawings are employed merely for the purpose of facilitating the description of the invention as a whole and not to define the limits thereof, reference 40 being had to the appended claims for this purpose.

In the drawings Figs. 1 and 2, with Fig. 2 below Fig. 1, illustrate diagrammatically 45 the circuits employed in the present invention.

The invention is illustrated as applied to 50 a small private branch exchange containing seven subscribers, an attendant's position and a central office trunk connection although it will be understood that this arrangement may be varied without departing from the spirit or scope of the invention.

Briefly stated, the system is preferably,

though not necessarily, of a full relay type 55 and provides for a number of subscribers' lines having access to a lesser number of link circuits, two of which are shown in Fig. 2. Each subscriber's line extends through a number of normal key contacts 60 under the control of the attendant and has associated therewith an individual relay mechanism which is operated upon the initiation of a call to seize an impulse controlling mechanism common to the subscribers' 65 lines. The seizure of this impulse controlling mechanism prevents the establishment of another call until the mechanism is again returned to normal, which occurs at approximately the time when the original calling 70 subscriber's line is connected to the called subscriber's line. In response to a series of impulses transmitted from the impulse sending device at the calling substation, the impulse controlling mechanism is 75 actuated to lock up one of a single set of counting relays which form a part of said mechanism. This single set of counting relays comprises a number of relays equal in 80 number to the maximum number of impulses transmissible in any one series by a single operation of the subscriber's calling dial. At the termination of said series of impulses an idle link circuit is selected by 85 a condition existent at the controlling mechanism. Switching devices individual to the link circuit are then operated to simultaneously energize other switching devices preferably in the form of junction relays and individual to the calling and called lines. 90 whereupon the called subscriber is signalled and upon the removal of his receiver from its switchhook the connection is established.

Provision is also made for interconnecting 95 a subscriber within the exchange and an attendant thereat, in which instance the subscriber sends nine impulses by dialing the digit 0 and the operation is then substantially the same as described in connection with the establishment of a call between two subscribers.

An attendant may, by the operation of 100 certain keys at her position, connect her line to a central office exchange and also connect a central office trunk to a subscriber's substation.

A subscriber may call a central office operator direct by dialing 1, whereupon the

impulse controlling mechanism will again select an idle link circuit. The selected link circuit through the simultaneous operation of junction relays is extended to a 5 central office trunk and upon the response of the operator the connection is established to the calling line through the trunk and link circuits.

On incoming calls from the central office, 10 the connection is first established to the attendant's position. The attendant may then manually signal the called subscriber and connect the central office trunk to his line by the operation of certain keys at the attendant's board. By providing an impulse 15 sending device at the attendant's position and a relay mechanism individual to the attendant's line similar to the mechanism provided for each subscriber, it will be apparent that the attendant may automatically 20 call a subscriber within the exchange or a central office operator.

It is believed that the system will now be fully understood from the following detailed 25 description of the operation in establishing various connections.

Let it first be assumed that the subscriber at substation A, whose number is 8, desires to converse with the subscriber at substation 30 B, whose number is 2. Upon the removal of the receiver from its switchhook at substation A, line relay 100 individual to the subscriber's line is energized over a circuit extending from grounded battery, winding, 35 back contact and inner right armature of relay 100, back contact and outer right armature of relay 101, right alternate contact of cutoff relay 102, the normal contacts of keys 103 and 104, the substation line loop, 40 left alternate contacts of relays 105, 102, 106 and 107 to ground. Energization of line relay 100 establishes a circuit for relay 105 extending from grounded battery, right winding of relay 105, front contact and 45 outer left armature of relay 100 to ground. Relay 108 is energized in parallel with relay 105 over a circuit extending from grounded battery left winding of relay 108, front contact and outer left armature 100 50 to ground. Attraction of the inner right armature of relay 100 closes a circuit for pulsing relay 109 of the impulse controlling mechanism common to all of the subscribers' lines, which circuit extends from grounded 55 battery, winding of relay 109, front contact and inner right armature of relay 100, back contact and outer right armature of relay 101, right alternate contact of relay 102, the subscriber's line loop, left alternate contact and armature of relay 105 to ground 60 through the dial tone apparatus DT. By the attraction of the outer right armature of relay 100, the energizing circuits for all other line relays individual to the other subscribers are opened, thus preventing said 65

other subscribers from seizing the common impulse controlling mechanism until the line relay of the calling subscriber releases which occurs shortly after the calling subscriber's dial has returned to normal. Relay 70 100, after becoming energized, is locked up over a circuit extending from grounded battery, winding of relay 100, alternate contact 110, winding of relay 111, alternate contact of relay 112, and right alternate contact of relay 106 to ground. Energization of relay 109 establishes a circuit for slow-to-release relay 107 extending from grounded battery, winding of relay 107, front contact and right armature of relay 109, and right alternate contact of relay 106 to ground. At the time relay 105 is energized the dial tone DT is applied to the calling line over the previously described circuit for relay 109. The calling subscriber upon hearing this dial tone may proceed to operate his impulse sending device in accordance with the digit of the wanted line which, as assumed, is No. 2.

Pulsing relay 109 responds to the interruptions in the line circuit and upon the first deenergization of said relay a circuit is established for slow-to-release relay 113 extending from grounded battery, winding of said relay, right armature and alternate contact of relay 107, back contact and right armature of relay 109 and right alternate contact of relay 106 to ground. Relays 107 and 113 being slow to release will remain energized during the transmission of impulses. Energization of relay 113 removes battery from the right armature thereof, and at its left armature closes a circuit for relay 112 extending from grounded battery, winding of said relay, front contact and left armature of relay 113, left armature and alternate contact of relay 107 to ground. Relay 112 energizes and locks up over the circuit extending from grounded battery, winding, front contact and left armature of said relay, left armature and alternate contact of relay 107 to ground.

Energization of relay 112 transfers the locking ground for relay 100 from the right alternate contact of relay 106 to the alternate contact and outermost right armature of relay 112. The first deenergization of pulsing relay 109 also establishes a circuit for relay 114 traceable from grounded battery, resistance 115, winding of relay 114, back contact and outer left armature of relay 116, left armature and back contact of relay 117, left armature and back contact of relay 109, left armature and alternate contact of relay 107 to ground. Relay 114 energizes and closes a circuit for counting relay 1', extending from grounded battery, winding of relay 1', front contact and right armature of relay 114, the alternate contacts of all of the counting relays, left armature

and alternate contact of relay 107 to ground. Counting relay 1' energizes and locks up through its right armature and alternate contact and the alternate contacts of the 5 succeeding counting relays to ground at relay 107. Energization of relay 114 also energizes relay 116 over a circuit extending from grounded battery resistance 115, winding, front contact and left armature of relay 114, left winding of relay 116, left armature and alternate contact of relay 107 to ground. Relays 114 and 116 lock up in this circuit and relay 109 is again operated at the termination of the first impulse. 10

15 The second deenergization of relay 109, in response to the interruption of the line circuit establishes a circuit extending from grounded battery, resistance 115, right armature and front contact of relay 116, front contact and left armature of relay 116, left armature and back contact of relay 117, left armature and back contact of relay 109, left armature and alternate contact of relay 107 to ground. The current 20 flowing over this circuit is diverted from relay 114 so as to short-circuit and cause the same to deenergize, but relay 116 remains energized over the circuit extending from grounded battery, right winding of relay 116, front contact and left armature of said relay and from thence over the previously described circuit to ground at the relay 107. The second counting relay (not shown) which is similar in all respects 25 to the succeeding counting relays is now energized over the circuit which extends from grounded battery through the winding of the relay, outer left armature and front contact of counting relay 1', front contact and left armature of relay 116 to ground at relay 107. Energization of the second counting relay breaks, at its alternate contact, the locking circuit for counting relay 1', which then deenergizes. The 30 second counting relay then locks up through the alternate contacts of the succeeding relays to ground at relay 107. The second operation of relay 109 at the termination of the second impulse causes relay 116 to release and also breaks the circuit for slow-to-release relay 113, which, after an interval of time, deenergizes. Slow-to-release relay 107 remains operated over its original energizing circuit. The foregoing operation 35 is repeated should a calling subscriber operate his dial to send further impulses. Upon the release of relay 113, a circuit is established from grounded battery, back contact and right armature of relay 113, winding of relay 106, innermost right armature and front contact of relay 112, left armature and alternate contact of relay 107 to ground, and relay 106 becomes energized in this circuit. The holding circuit for relay 107 is then broken at the right armature of relay 106 but relay 107 does not release until after a short interval. 40

Battery, now connected to the right armature and back contact of relay 113, is also transmitted to relay 118, but if the called line is idle this relay will not operate. Relay 117 will, however, be energized over a circuit traceable from grounded battery, back contact and right armature of relay 113, right armature and back contact of relay 118, winding of relay 117, innermost right armature and front contact of relay 112, left armature and alternate contact of relay 107 to ground. Energization of relay 117 closes a circuit for relay 101 extending from grounded battery, right winding of relay 101, alternate contact thereof, front contact and left armature of relay 100, front contact and outer right armature of relay 117, back contact and outer left armature of relay 118, middle right armature and front contact of relay 112, left armature and alternate contact of relay 107 to ground. Relay 101 upon energizing will lock up through its alternate contact and inner right armature to the subscriber's line loop. 45

Assuming that the first link circuit shown in Fig. 2 is idle, relay 200 associated therewith will be in normal position, and upon operation of relay 117, circuits will be closed in parallel for relays 201, 202, 203, extending from grounded battery through the windings of said relays, back contact and lower armature of relay 200, front contact and inner right armature of relay 117, back contact and outer left armature of relay 118, middle right armature and front contact of relay 112, left armature and alternate contact of relay 107 to ground. If the first link is busy, relay 200 will be energized and relays of the next idle link similar to relays 201, 202 and 203 will be energized over the circuit extending through the front contact and lower armature of said relay 200. Energization of relay 202 closes a circuit for junction relay 204, individual to the calling subscriber's line, which circuit extends from grounded battery, left winding of relay 204, lowermost armature and front contact of relay 202, conductor 8 (Fig. 1), front contact and inner left armature of relay 100, front contact and outer right armature of relay 117, back contact and outer left armature of relay 118, middle right armature and front contact of relay 112, left armature and alternate contact of relay 107 to ground. Simultaneously an energizing circuit is closed for junction relay 205 of the called subscriber's line extending from grounded battery, left winding of relay 205, inner lower armature and front contact of relay 202, conductor 2, which extends through the front contact and middle left armature of the second counting relay which is now energized and locked up, right armature and alternate contact of relay 106. 50

55

60

65

to ground. The calling and called lines are now connected through the link circuit. At the same time that junction relays 204 and 205 are energized, a circuit is also established for relay 206 extending from grounded battery, winding of said relay, armature and back contact of relay 208, inner upper armature of relay 201, conductor L, back contact and inner left armature of counting relay 1', right armature and alternate contact of relay 106 to ground. Relay 206 energizes and locks up over a circuit extending from grounded battery, winding of said relay, armature and back contact of relay 208, outer right armature and front contact of relay 206 to ground. Slow-to-release relay 207 is now energized over a circuit extending from grounded battery, winding of said relay, outer left armature and front contact of relay 206 to ground. Energization of the latter relay also provides a holding circuit for relay 105 extending from grounded battery, left winding of relay 105, back contact and left armature of cutoff relay 102, outermost left armature and front contact of relay 204, innermost left armature and front contact of relay 206 to ground. It will be recalled that relay 101 has been energized and upon the energization of junction relay 204 and relay 207 a locking circuit is established for relay 204, which extends from grounded battery, front contact and left armature of relay 101, inner right armature and alternate contact of relay 105, conductor 119, right armature, front contact and winding of relay 204, left armature and front contact of relay 207 to ground. Relay 108 is also locked up in this circuit in series with relay 204. A locking circuit for junction relay 205 individual to the called subscriber's line is also established, which circuit extends from grounded battery, winding of cutoff relay 102 individual to the called line, right alternate contact of relay 105, also individual to the called line, conductor 119, right armature, front contact and right winding of relay 205, left armature and front contact of relay 207 to ground. Relay 102 of the called line is energized in this circuit. The foregoing operation beginning with the breaking of the circuit of relay 107 by the energization of relay 106 takes place before relay 107 releases and upon deenergization thereof, the holding ground for relay 106 is removed, causing said relay to deenergize. The locking circuit for relay 112 is also broken whereupon the latter relay will release. Release of relay 107 removes the locking ground for the second counting relay which then releases. Relays 100 and 111, which were locked up to ground through the alternate contact, and outermost right armature of relay 112 become deenergized when relay 112 is released. Deenergization of relay 100 breaks the circuit for relay 109 which

then releases. Relays 117, 201, 202 and 203 which found ground at the left armature and alternate contact of relay 107 through the innermost and middle right armature of relay 112 also release. Deenergization of relay 201 closes a circuit for relay 200 extending from grounded battery, upper winding of relay 200, back contact and uppermost armature of relay 201, front contact and right armature of relay 207 to ground. Relays 200 and 207 remain energized during the establishment of a call and the energization of relay 200 causes the selection of the next idle link circuit. The impulse controlling mechanism common to all of the subscriber's lines is now again in normal position and ready to be operated by the initiation of another call. Upon the energization of relay 206, ringing current is applied to the called subscriber's line over a circuit extending from a suitable source of ringing current through the winding of marginal relay 208, front contact and right armature of relay 206, front contact and middle left armature of relay 205, the called subscriber's line loop including the ringer apparatus, outer left armature and front contact of relay 205, inner right armature and front contact of relay 206 to ground. Ringing tone is also applied to the calling subscriber's line through relay 208, front contact and right armature of relay 206, front contact and middle left armature of relay 204, winding of relay 121, right armature and back contact of relay 102, condenser 145 and left winding of relay 101 to ground, then by induction from the left winding of relay 101 into the right winding thereof, the alternate contact and inner right armature of relay 101, right alternate contact of relay 102, the subscriber's line loop, left alternate contact and armature of relay 105 to ground. If the called subscriber answers, the removal of his receiver from its switchhook will cause sufficient current to flow through relay 208 to energize same, whereupon the locking circuit of relay 206 is broken and the same releases. Removal of ground from inner left armature and front contact of relay 206 causes relay 105 to release. The holding circuit for relay 207 is also broken at the outer left armature and front contact of relay 206, but relay 207, being slow to release, does not deenergize immediately. When relay 105 releases a circuit is closed for the cutoff relay 102 of the calling subscriber's line, which circuit is traceable from grounded battery, winding of relay 102, right alternate contact of relay 105, conductor 119, right armature, front contact and right winding of relay 204, left armature and front contact of relay 207 to ground. Relay 102 attracts its armatures and connects the calling subscriber's line to the link circuit and called subscriber lines. Relay 121 is then operated in series with the

calling subscriber's line loop and will establish another holding circuit for relay 207 before the same can release which circuit extends from grounded battery, winding of 5 relay 207, front contact and innermost left armature of relay 204, front contact and armature of relay 121, left armature and front contact of relay 108 to ground. At the time cutoff relay 102 of the calling sub-

10 scriber's line is operated the locking circuit for relay 101 extending through right alternate contact and inner right armature thereof, and from thence over the subscriber's line loop is broken and relay 101 releases.

15 Conversation between the calling and called subscribers may now proceed.

If the called line is busy, relay 118 will operate over a circuit extending from 20 grounded battery, back contact and right armature of relay 113, winding of relay 118, lowermost armatures and back contacts of 25 relays 203' and 203, innermost left armature and front contact of the second counting relay, which has become energized, thence over 30 a conductor similar to the one leading to the front contact and innermost left armature of counting relay 8', said conductor extending to the relay mechanism individual to the called subscriber's line, conductor 119, also individual to the called line, right armature, front contact and right winding of 35 relay 205, left armature and front contact of relay 207 to ground. Energization of relay 118 prevents relay 117 from being operated and closes a circuit for relay 101 of the calling line which circuit extends from grounded battery, right winding of relay 101, alternate contact thereof, front contact and left armature of relay 100 40 which has not as yet deenergized, due to the slow release of relay 107, front contact and outer left armature of relay 118, middle right armature and front contact of relay 112, left armature and alternate contact of 45 relay 107 to ground. Relay 101 locks up over the circuit traceable from grounded battery, right winding, alternate contact and inner right armature of relay 101, right alternate contact of relay 102, calling subscriber's 50 loop, left alternate contact and left armature of relay 105 to ground. As previously described, upon the release of relay 107, the entire impulse controlling mechanism returns to normal including relay 118,

55 which was locked up through its winding, front contact and inner left armature and the middle armature and front contact of relay 112 to ground at relay 107. Release of relay 112 causes the deenergization of relay 100 which breaks the holding circuit for relay 105 and causes the latter to release. The locking ground for relay 101 is then transferred from the left armature of relay 105 to the left alternate contact of said re-

60 lay, left alternate contacts of relays 102, 106

and 107. Release of relay 105 applies a busy tone to the calling subscriber's line extending from ground through the busy tone apparatus BZ, outer right armature and back contact of relay 105, right winding of relay 70 101 to grounded battery. This busy tone is transmitted through the alternate contact and inner left armature of relay 101 to the subscriber's line loop.

Upon hearing this busy tone, the calling subscriber replaces his receiver upon its switchhook, and thereby breaks the locking circuit for relay 101 which then releases. At the time relay 100 became deenergized, the holding circuit for relay 108 is also broken at the outer left armature and front contact of relay 100 and relay 108 also releases.

Should all of the link circuits be busy, a circuit will be established for relay 118 extending from ground, front contact and upper armature of relay 200 to the first link circuit, upper armature and front contact of relay 200' individual to the second link circuit, the upper armatures and front contacts of the individual relays of all other link circuits, back contacts and lowermost armatures of relays 203 and 203' and similar relays of said other link circuits, winding of relay 118, right armature and back contact of relay 113 to grounded battery. Energization of relay 118, establishes an energizing circuit for relay 101 and applies busy tone to the calling subscriber's line, as previously described. Upon hearing the 100 busy tone, the calling subscriber replaces his receiver upon its switchhook and causes the relay 101 to deenergize. Relay 118 remains energized until one of the link circuits becomes idle, at which time the associated individual relay similar to relay 200 will deenergize and cause the release of relay 118.

At the termination of the conversation, in the event of a successful establishment of a call, the calling subscriber, by replacing his receiver upon its switchhook, causes the relay 121 to release. This breaks the circuit for relay 207 which extended through the front contact and armature of relay 121 to ground at the left armature of relay 108 and relay 207 then releases. Removal of ground from the left armature of relay 207 breaks the locking circuits for relays 102, 108, 204 and 205, which relays then release. The mechanism is now in its normal position and again ready to be operated upon the initiation of another call.

To call an attendant from a subscriber's substation, the operation of the impulse controlling mechanism and the switching devices individual to the seized link circuit is the same as described in connection with the call between two subscribers, with the following exceptions.

After the calling subscriber has removed

his receiver from its switchhook and hears the dial tone, the impulse sending device at the substation is operated to transmit nine impulses to energize and lock up counting relay O'. Assuming that the first link circuit and the attendant's position is idle, a circuit will be established for relay 210 extending from grounded battery, winding of said relay, inner upper armature and front contact of relay 202, conductor O, front contact and outer left armature of counting relay O', right armature and alternate contact of relay 106, to ground. The operation of relay 210 joins adjacent ends of two permanently paired link circuits to form a loop circuit for connecting the operator's telephone line to the calling subscriber's line. Relay 210 locks up through its winding, front contact and lower armature to ground at the left armature and front contact of relay 207. A circuit is then completed for a ring-down drop relay (not shown) at the attendant's position to indicate a call from a subscriber, and the attendant at said position operates a key to shift contacts 141. A circuit is now closed from the subscriber's substation, through the armatures of cutoff relay 102, two outer left armatures and front contacts of junction relay 204, the upper armatures and front contacts of relay 210, contacts 141, to the attendant's telephone. The battery key including contacts 135 and 136 may be operated by the attendant to furnish talking current to the attendant's line from relay 211.

If the attendant is busy when the call from the subscriber is initiated, relay 118 will be energized over a circuit extending through the inner left armature and front contact of counting relay O' and over the conductor SO, to a ground (not shown) at the attendant's position. Energization of relay 118 will produce the same results as previously described and a busy tone will be applied to the calling subscriber's line.

Should a subscriber desire a connection to a central office operator, the call is initiated by the removal of the receiver from its switchhook which energizes line relay 100, as previously described and upon energization of relay 105, the dial tone is applied to the calling line. The sending device of the calling subscriber is operated to send one impulse which will cause counting relay 1' to energize and lock up, as previously set forth. At the termination of the single impulse, relay 109 remains energized and causes the release of relay 113. This closes the aforementioned circuit for relay 117 providing there is an idle central office trunk. Relay 106 is also energized by the release of relay 113. Relays 201, 202 and 203 are then energized in parallel through the back contact and lower armature of relay 200 to ground at left armature and alternate con-

tact of relay 107. Counting relay 1', being locked up to ground at the left alternate contact of relay 107, will not deenergize until said relay 107 releases and upon energization of relay 201, an energizing circuit will be established for relay 209 extending from grounded battery, winding of relay 209, lower armature and front contact of relay 201, conductor T, front contact and inner left armature of relay 1', right armature and alternate contact of relay 106 to ground. Energization of relay 117 also establishes the previously described energizing and locking circuits for relay 101. Energization of relay 209 closes a circuit for relay 207, extending from grounded battery, winding of relay 207, outer left armature and front contact of relay 209 to ground. Energization of relay 207 connects ground to the left armature thereof and thereby closes the locking circuit for relays 108 and 204 as previously described. When relay 106 is energized, the holding ground for relay 107 is removed and this relay, after an interval, releases and causes relay 112 to deenergize. The release of relay 107 breaks a circuit for relay 106, but this relay being slow to release, does not deenergize at this time. Release of relay 112 causes relay 100 to deenergize, which, in turn, breaks the energizing circuit for relay 105. Before relay 106 can release, the following action takes place: Upon the release of relay 105, a circuit is established for cutoff relay 102 extending from grounded battery, winding of relay 102, right alternate contact of relay 105, conductor 119, right armature, front contact and right winding of relay 204, left armature and front contact of relay 207 to ground. Cutoff relay 102, energizing, extends the calling subscriber's line and closes a circuit for line relay 122 extending from grounded battery, right winding of relay 122, left alternate contact of cutoff relay 123, front contact and inner left armature of relay 209, back contact and inner left armature of relay 206, front contact and outermost left armature of relay 204, left armature and alternate contact of cutoff relay 102, the subscriber's line loop, alternate contact and right armature of relay 102, winding of relay 121, middle left armature and front contact of relay 204, right armature and back contact of relay 206, inner right armature and front contact of relay 209, right alternate contact of relay 123 and left winding of relay 122 to ground. Relay 121 is energized in this circuit with the same result as described in connection with the establishment of a call between two subscribers within the exchange. Relay 122, upon energizing, establishes a circuit for slow-to-release relay 124, extending from grounded battery, winding of relay 124, front contact and left armature of relay 122 to ground. Relay 124 ener-

gizes and establishes a locking circuit for relay 209 extending from grounded battery, winding, outer right armature and front contact of relay 209, left armature and front contact of relay 124 to ground. As soon as this locking circuit for relay 209 is established, relay 106 releases and the common impulse controlling mechanism is again restored to normal.

10 At the time relay 107 releases, the energizing circuit for relays 201, 202 and 203 is broken and said relays restore, thus closing a circuit for relay 200 extending from grounded battery, left winding of relay 200, back contact and uppermost armature of relay 201, front contact and right armature of relay 207 to ground. Relay 200 energizes and remains in this condition until the call is terminated, thereby extending another call 15 to the next idle link circuit.

At the time of the energization of relay 122, a circuit is established for line relay 126 at the central office operator's position which circuit extends from grounded battery, left winding of relay 126, outer armature and back contact of cutoff relay 127, front contact and right armature of relay 122 and alternate contact of slow-to-release relay 128 to ground. Relay 126 energizes 20 and operates the signaling lamp at the central office operator's position to indicate an incoming call on the trunk with which said lamp is associated. The central office operator then plugs into the jack and thereby 25 operates the cutoff relay 127 in the usual manner to extinguish the lamp. By plugging in, a circuit is also closed for relay 129 which is bridged across the line and said relay energizes. A circuit is then established for 30 relay 128 extending from grounded battery, winding of said relay, front contact and armature of relay 129 to ground. Relay 128 then energizes and closes a circuit for cutoff relay 123 which circuit is traceable from 35 grounded battery, winding of relay 123, front contact and right armature of relay 124 which has already been energized, right armature and alternate contact of relay 128 to ground. Energization of relay 123 breaks 40 the circuit for line relay 122, but relay 124 which was originally energized by the ground at the left armature of relay 122, does not release due to the ground at the front contact and outer left armature of relay 123. Energization of the latter relay 45 also extends the calling line to the central office operator's position and in doing so energizes relay 130. Relay 131 is then energized over a circuit extending from grounded battery, winding of relay 131, front contact and left armature of relay 130 to ground. Relay 131, by attracting its left armature, breaks the energizing circuit for 50 relay 129 which then releases. Relay 128 is then energized by the ground at the right

armature and front contact of relay 130. Conversation may now proceed between the calling subscriber and the central office operator through the resistance 132.

At the termination of the call, the calling subscriber, by replacing his receiver, deenergizes the relay 121, which causes the restoration of the relay mechanism associated with the seized link circuit with the exception of relay 209, in the same manner as described in connection with the release of said mechanism at the termination of a call between two subscribers within the exchange.

When the calling subscriber replaces his receiver, the energizing circuit for relay 130 is also broken and this relay releases, causing the deenergization of relays 128 and 131. Release of relay 128 breaks the circuit for cutoff relay 123 which then restores and in turn causes the release of relay 124. The locking circuit for relay 209 is then broken at the left armature and front contact of relay 124, and the mechanisms associated with the link and central office trunk circuits are then in normal positions. At the time of the replacing of the receiver upon its switchhook at the calling substation, a suitable signal (not shown) at the central office operator's position is operated to indicate the termination of the call and the operator may then remove the plug from its jack.

On an incoming call from the central office to one of the subscribers within the exchange, a call is first extended to an attendant's position at the exchange. The central office operator, by plugging into the jack, operates relay 129 which closes the previously mentioned energizing circuit for relay 128. This relay, upon energizing, closes a circuit for relay 133 individual to the trunk leading to the attendant's position which circuit extends from grounded battery, winding of relay 133, left armature and front contact of relay 128 to ground. At the time the operator plugs in, she may operate her ringing key which will energize relay 130 to ground through the condenser 143 with the results to be later described. Energization of relay 133 operates a signal 100 at the attendant's position to indicate an incoming call over the particular trunk circuit and the attendant then operates the key contacts 134 to connect her line to said trunk. Energizing circuit for line relay 122 is then established and extends from grounded battery, right winding of relay 122, left alternate contact of relay 123, contact 135, battery key, the left key contact 134 in its operated position, left key contacts of the other attendant's keys in their normal position, the attendant's line loop, right key contacts of said other keys, right key contact 134 in its operated position, key contact 136, right alternate contact of relay 110 115 120 125 130

123 and left winding of relay 122 to ground. Operation of relay 122 closes a circuit at its left armature for relay 124. Relay 125 is then energized and applies ground to its 5 armature which closes an energizing circuit for relay 200 so that the associated link and central office circuits cannot be seized. Relay 123 is now energized over the previously 10 described circuit to ground through the right armature of relay 128. Relay 123, by energizing breaks a circuit for relay 122 and provides a holding ground for relay 124. At the time relay 130 is operated, relay 131 is energized and breaks the circuit 15 for relay 129. Relay 130 in operating, also provides a holding ground for relay 128. The attendant may now converse with the central office operator and upon determining the wanted subscriber may operate the 20 holding key 137 to hold the central office connection. Assuming that the subscriber A is wanted, the attendant then operates key contacts 138 of the key 104 and connects a source of ringing current to the subscriber's 25 line, which extends from the ringing current generator 139, right key contact 138, the subscriber's line loop and left key contact 138 to ground. When the subscriber answers, the attendant restores the contacts 30 138 to normal and operates contacts 140 to connect the subscriber's line loop to the trunk circuit, whereupon contacts 134 of the holding key 137 may be restored and conversation may proceed between the calling 35 and called subscribers. At the termination of the call, mechanism associated with the central office trunk circuit is returned to normal in the same manner as previously described and the attendant, upon receiving a 40 suitable signal, may restore the operated contacts 140, whereupon the parts are again in normal position.

A subscriber may be connected to central 45 office through an attendant instead of direct as previously described in which event the subscriber will first call the attendant by operating counting relay O', and after the establishment of the connection the subscriber may then replace his receiver. The 50 attendant then operates the key contacts 134, whereupon a circuit is established for line relay 122 with the same results as described in connection with a call direct from a subscriber to the central office. Upon obtaining 55 the connection to the central office operator the attendant may operate the holding key 137 and then ring the subscriber as previously set forth. When the subscriber responds 60 the attendant operates key contacts 140 and connects the central office trunk direct to the subscriber's line. When the contacts 140 are operated, a circuit is closed for the cut-off relay 102 individual to the calling subscriber's line which circuit is traceable from 65 grounded battery, winding of relay 102,

right alternate contact of relay 105, contact 142, and left winding of relay 125, to ground. At the time relay 125 is energized, a circuit is established for relay 200 extending from grounded battery, upper winding of relay 200, back contact and uppermost armature of relay 201, left armature and front contact of relay 125, to ground. Energization of relay 200 indicates a busy 70 condition of the particular link and trunk 75 circuits seized, and operates to extend another call from a subscriber to central office to the next idle central office link circuit.

What is claimed is:

1. In a telephone exchange system, a 80 calling and a called subscriber's line, means for extending said calling line, an impulse controlling mechanism to which said calling line is extended and which is common to said lines, relays simultaneously actuated by said 85 impulse controlling mechanism for connecting said calling line to said called line, and means under the sole control of the calling subscriber for releasing the established connection. 90

2. In a telephone exchange system, calling and called subscribers' lines, a relay mechanism individual to the calling line, a link circuit for joining said calling and called lines, an impulse controlling mechanism, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and means for operating the switching means individual to said calling and called lines. 100

3. In a telephone exchange system, calling and called subscribers' lines, a relay mechanism individual to the calling line, a link circuit for joining said calling and called lines, an impulse controlling mechanism, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and an electromagnetic means under the control of said impulse controlling mechanism for operating the switching means individual to said calling and called lines. 115

4. In a telephone exchange system, calling and called subscribers' lines, a relay mech- 120

130

- anism individual to the calling line, a link circuit for joining said calling and called lines, an impulse controlling mechanism including a set of counting relays, means for energizing one of said counting relays, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to the energization of said counting relay and means for operating the switching means individual to said calling and called lines whereby the same are simultaneously connected to said link circuit.
- 5 5. In a telephone exchange system, calling and called subscribers' lines, a relay mechanism individual to the calling line, a link circuit for joining said calling and called lines, an impulse controlling mechanism including a set of counting relays, means for energizing one of said counting relays, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to the energization of said counting relay and means for operating the switching means individual to said calling and called lines whereby the same are simultaneously connected to said link circuit.
- 10 6. In a telephone exchange system, calling and called subscribers' lines, a line relay individual to the calling line, a link circuit for joining said calling and called lines, an impulse controlling mechanism including a set of counting relays, means for energizing one of said counting relays, junction relays individual to said calling and called lines for connecting the same to said link circuit, the operation of the junction relay individual to the calling line being dependent upon the energization of said line relay and upon an electrical condition at said impulse controlling mechanism, and the junction relay individual to said called line being dependent upon the energization of said counting relay and means under the control of said impulse controlling mechanism for simultaneously operating said junction relays.
- 15 7. In a telephone exchange system, a calling and a called subscriber's line, means individual to said calling line for extending same, an impulse controlling mechanism to which said calling line is extended and which is common to said lines, and relays actuated simultaneously for connecting said calling line to said called line, one of said relays being individual to the calling line and controlled by said impulse controlling mechanism and said individual means, and the other relay being individual to the called line and controlled only by said impulse controlling mechanism.
- 20 8. In a telephone exchange system, calling and called subscribers' lines, a relay mechanism individual to the calling line, a link circuit for joining said calling and called lines, an impulse controlling mechanism including a set of counting relays, means for energizing one of said counting relays, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to the energization of said counting relay and electro-magnetic means under the control of said impulse controlling mechanism for simultaneously operating the switching means individual to said calling and called lines.
- 25 9. In a telephone exchange system, calling and called subscribers' lines, a line relay individual to the calling line, a link circuit for joining said calling and called lines, an impulse controlling mechanism including a set of counting relays, means for energizing one of said counting relays, junction relays individual to said calling and called lines for connecting the same to said link circuit, the operation of the junction relay individual to the calling line being dependent upon the energization of said line relay and upon an electrical condition at said impulse controlling mechanism, and the junction relay individual to said called line being dependent upon the energization of said counting relay and means under the control of said impulse controlling mechanism for simultaneously operating said junction relays.
- 30 10. In a telephone exchange system, a calling and a called subscriber's line, means individual to said calling line for extending same, an impulse controlling mechanism to which said calling line is extended and which is common to said lines, and relays actuated simultaneously for connecting said calling line to said called line, one of said relays being individual to the calling line and controlled by said impulse controlling mechanism and said individual means, and the other relay being individual to the called line and controlled only by said impulse controlling mechanism.
- 35 11. In a telephone exchange system, calling and called subscribers' lines, a relay mechanism individual to the calling line, a link circuit for joining said calling and called lines, an impulse controlling mechanism including a set of counting relays, means for energizing one of said counting relays, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to the energization of said counting relay and electro-magnetic means under the control of said impulse controlling mechanism for simultaneously operating the switching means individual to said calling and called lines.

In witness whereof, I hereunto subscribe my name this 9th day of July, A. D. 1919.

WARREN W. CARPENTER.

DISCLAIMER.

1,506,884.—*Warren W. Carpenter, Brooklyn, N. Y. TELEPHONE-EXCHANGE SYSTEM.* Patent dated September 2, 1924. Disclaimer filed April 4, 1928, by the assignee, *Western Electric Company, Incorporated.*

Hereby enters this disclaimer to that part of the claims in said specification which are in the following words to wit:

“1. In a telephone exchange system, a calling and a called subscriber's line, means for extending said calling line, an impulse controlling mechanism to which said calling line is extended and which is common to said lines, relays simultaneously actuated by said impulse controlling mechanism for connecting said calling line to said called line, and means under the sole control of the calling subscriber for releasing the established connection.

“2. In a telephone exchange system, calling and called subscribers' lines, a relay mechanism individual to the calling line, a link circuit for joining said calling and called lines, an impulse controlling mechanism, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and means for operating the switching means individual to said calling and called lines.

“3. In a telephone exchange system, calling and called subscribers' lines, a relay mechanism individual to the calling line, a link circuit for joining said calling and called lines, an impulse controlling mechanism, switching means individual to said calling and called lines for connecting the same to said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and an electromagnetic means under the control of said impulse controlling mechanism for operating the switching means individual to said calling and called lines.”

“7. In a telephone exchange system, a calling and a called subscriber's line, means individual to said calling line for extending same, an impulse controlling mechanism to which said calling line is extended and which is common to said lines, and relays actuated simultaneously for connecting said calling line to said called line, one of said relays being individual to the calling line and controlled by said impulse controlling mechanism and said individual means, and the other relay being individual to the called line and controlled only by said impulse controlling mechanism.”
